(57) **CLAIM**

The ornamental design for an electrotherapy device, as shown and described.

DESCRIPTION

FIG. 1 is a perspective view of an electrotherapy device showing my new design.

FIG. 2 is a front view thereof, the rear view is a mirror image.

FIG. 3 is a left side view thereof.

FIG. 4 is a right side view thereof.

FIG. 5 is a top view thereof, shown enlarged in scale.

FIG. 6 is a bottom view thereof, shown enlarged in scale.

FIG. 7 is a view of an electrotherapy device in a first use state.

FIG. 8 is a view of an electrotherapy device in a second use state; and,

FIG. 9 is a view of an electrotherapy device in a third use state.

The broken lines in FIGS. 7-9 depict environment only and form no part of the claimed design.
